[57] CLAIM

The ornamental design for a frame for holding linoleum sample, as shown and described.

DESCRIPTION

FIG. 1 is a front view of a frame for holding a linoleum sample and showing my new design;

FIG. 2 is a top view thereof;

FIG. 3 is a right side view thereof;

FIG. 4 is a left side view thereof;

FIG. 5 is a rear view thereof;

FIG. 6 is a bottom view thereof;

FIG. 7 is an enlarged fragmentary left side view taken in the direction of the arrows on line 7—7 of FIG. 1;

FIG. 8 is an enlarged fragmentary sectional view taken in the direction of the arrows on line 8—8 of FIG. 2;

FIG. 9 is an enlarged fragmentary sectional view taken in the direction of the arrows on line 9—9 of FIG. 1;

FIG. 10 is an enlarged fragmentary sectional view taken in the direction of the arrows on line 10—10 of FIG. 1; and

FIG. 11 is an enlarged fragmentary sectional view taken in the direction of the arrows on line 11—11 of FIG. 1.
